T. J. ALDRIDGE,
GARMENT STRETCHING DEVICE,
APPLICATION FILED MAR. 1, 1915.

1,153,150.

Patented Sept. 7, 1915.

UNITED STATES PATENT OFFICE.

THOMAS J. ALDRIDGE, OF ROCHESTER, NEW YORK.

GARMENT-STRETCHING DEVICE.

1,153,150.

Specification of Letters Patent.

Patented Sept. 7, 1915.

Application filed March 1, 1915. Serial No. 11,334.

To all whom it may concern:

Be it known that I, THOMAS J. ALDRIDGE, a citizen of the United States residing at Rochester, in the county of Monroe and State of New York, have invented certain new and useful Improvements in Garment-Stretching Devices, of which the following is a specification.

The object of the present invention, which relates to garment stretching devices, is to provide a simple article of manufacture designed particularly, not only for retaining in shape, but removing from neckwear and similar articles, wrinkles resulting from use thereof, without resorting to pressing their surfaces.

Neckwear is customarily made of delicate fabrics, and the process of pressing the same with a heated iron, usually resorted to, is deleterious to the material as well as troublesome so that my aim has been to overcome these disadvantages by constructing a device on which the articles may be disposed when not in use, having means for retaining and imparting slight tension thereto for the purpose hereinbefore specified.

A still further object of my device is to provide tension means above mentioned of a special form, such that variable tension may be imparted to the neckwear in the action of clamping such articles on the body member of the device.

These and such other objects as may hereinafter appear are attained by the novel construction, combination and arrangement of parts to be hereinafter specifically described and claimed.

Reference will now be had to the accompanying drawing forming a part of this specification, wherein:

Figure 1 is a front elevation of a device constructed in accordance with my invention. Fig. 2 is a side elevation thereof; and Figs. 3, 4 and 5 are respectively vertical and transverse sectional views taken on the several plane lines 3-3, 4-4, and 5-5 of Fig. 1.

Throughout the following detail description, and on the several figures of the drawings, similar parts are referred to by like reference characters.

Referring to the drawing, the embodiment of my device consists of a body member or support 1 which may be of any desired configuration and material, being preferably composed, however, of sheet metal

of plate-like form and elongated so as to easily accommodate the garments or articles of neckwear designed to be disposed thereon in the manner hereinafter described. The body member 1 is preferably provided with a flange or upturned edge extending completely around the same, and is furthermore cut-away at its upper portion so as to provide one or more arms 3 over which the neckwear articles indicated at 4 are supportingly engaged. It will be understood, of course, that one or more neckties may easily be disposed over a single arm but I prefer to provide at least two in order to most easily accommodate the neckwear and facilitate ready removal thereof from the stretching device.

Loosely and pivotally secured adjacent to the bottom portion of the body member 1, and at one side thereof is provided a garment engaging member or bar 5 which is adapted in performing its several functions to extend transversely of the body member and to engage the neckwear so as to hold or clamp the same onto the member 1. For this purpose the plate-like member 1 is so cut-away at its edge opposite the connection 5 for the bar 5 so as to form a hook or lock member 6, the same lying in the plane corresponding to the flange 2 so as to permit the free end of the bar 5 to be engaged therebeneath. The functions of this bar are peculiar and in explanation, it will be noted that the loose pivotal connection thereof permits said bar to be moved quite readily in a lateral direction or rotatably to a limited extent. The main purpose of this bar, in addition to positively holding the neckwear on the body member 1 is to impart tension thereto for the purpose of keeping the article of neckwear in shape or of removing wrinkles therefrom that may have been due to the ordinary use of the neckwear.

The initial movement of the member mentioned transversely of the body member 1 engages said bar with the upper layer or surface of the neckwear 4 and the free end of the bar by lateral movement is engaged beneath the locking hook 6. This lateral movement of the member imparts tension or stretching action to the necktie or ties as the case may be. Under ordinary conditions, this tension is sufficient to maintain the article in good shape but where it is necessary to afford greater tension than comprehended by the above description, as for instance

when it is desired to remove wrinkles, the outer end of said bar, which is preferably slightly upturned, is moved rotatably. By reason of the engagement of the bar with the upper surface of the tie and the friction necessarily incidental to such engagement, the rotation of the bar about its longitudinal axis a partial rotation will further cause the lower end of the tie to be pulled, or 10 rolled downwardly and thereby greater tension is imparted to the article. As shown in the drawing, the bar 5 may be provided at its outer extremity with a manipulating head or enlargement 7.

15 It will be understood from the foregoing description that the neckwear is generally applied to the article by folding the same in half and slipping said tie over one of the arms 3 at the upper portion of the body member 1, both of the neckwear extremities being engaged beneath the bar member 5 above described.

It will be apparent that slight changes in the configuration and details of construction of this device may be made without departing from the spirit of the invention and within the scope of the claims hereto appended.

Having thus described my invention, what I claim as new is:

30 1. A device of the class described, comprising a body of plate-like form, a garment holding member at one end of the body, clamping means disposed adjacent to the other end and comprising a bar pivotally connected at one side of the body and movable to a position transversely of the same for engaging and clamping the garment

against the face of the body, said bar being movable longitudinally of the body to draw 40 the garment for stretching the same, and means for holding the bar in the stretching position aforesaid and with which the bar engages on the longitudinal movement.

2. A device of the class described comprising a body member for holding neckwear or the like, means connected to the body member for engaging the neckwear and movable laterally to impart tension and also movable rotatably to impart an increase 50 50 to the neckwear, and a locking member on the plate member with which the bar engages when moved in the last-mentioned direction to hold the garment in stretched condition.

3. As a new article of manufacture, a garment stretcher consisting of a body member composed of sheet material, said material being cut-way adjacent its upper portion to form a sustaining arm for holding neckwear or the like, said material being cut adjacent its lower portion to form a hook member at one side, and a bar member loosely pivoted to the opposite side and adapted to be disposed transversely of the 60 65 body member for engaging neckwear articles sustained thereby and engageable with the hook member aforesaid for holding said articles upon the body member.

In testimony whereof I affix my signature in the presence of two witnesses.

THOMAS J. ALDRIDGE.
